(57) **CLAIM**

The ornamental design for a cryogenic therapeutic device, as shown and described.

DESCRIPTION

1. Cryogenic therapeutic device

1.1 : Perspective

1.2 : Front

1.3 : Back

1.4 : Left

1.5 : Right

1.6 : Top

1.7 : Bottom

The broken line portion of the figure drawings is included to show portions of the article that form no part of the claimed design.
